IRA EDWARD SMITH, OF STOCKTON, CALIFORNIA.

THERMOSTAT SWITCH.

Application filed May 8, 1925. Serial No. 28,847.

This invention relates to improvements in electric switches of the type actuated by a movable element containing an expandable fluid sensitive to variations in temperature, 5 and whose expansion or contraction causes the movement of such element.

The principal object of my invention is to provide a switch of this general character, of a type usable either in connection 10 with air, or with steam and hot water, having a plurality of separate switch contacts, mounted to be actuated in common by a single liquid containing element, and so arranged that the times of opening or closing 15 of the contacts will be different from each other.

A further object is to provide a means for adjusting the different contacts relative to each other, so that the times between 20 their operation may be altered at will. In other words, apart from and without interference with any of the ordinary temperature regulating means commonly provided with such instruments, and which controls 25 the temperature at which one set of the contacts will be opened, I have arranged for enabling the other set of contacts to be adjusted so that they may be set to be opened or broken at any point in a reasonable range 30 of differences of temperature with respect to the temperature necessary to open the first contacts.

This arrangement enables a flexibility of 35 the control of the mechanism controlled by the switch to suit different conditions to be had, which it is impossible to obtain with only a single set of contacts, or with a plurality of contacts so arranged that they all open simultaneously, or so that their relative times of opening are fixed and unchangeable.

Another object is to employ contacts of 45 such a nature that a current of large amperage may be passed through the same without danger of arcing or burning the points as they are opened or closed, and of a type which will never become corroded or pitted, or undergo any deterioration or wear regardless of the length of service.

50 I have particularly in mind to employ this switch in connection with my oil burner system, filed November 17th, 1924, Serial No. 750,248.

55 This system includes a rotary burner plate, and a motor for both feeding oil to the burner plate and for rotating the same.

When the fire is first started, the full strength of the motor, and consequently a heavy flow of oil to the plate is desirable in order to quickly raise the temperature to 60 the desired degree. After such degree is reached it is desirable to reduce the volume of the fire (which is governed to a certain extent by the speed of the motor) in order to maintain the temperature in that degree 65 without actually causing the fire to go out. It is further desirable that this should be accomplished automatically and without the necessity of an attendant being on hand to control the motor.

70 Should the heat continue to rise in the furnace to a further degree for some reason, or in the room in which one of the thermostat switches is located, it is then desirable to discontinue the operation of the motor 75 and the feeding of the oil completely, until the temperature has been restored to a pre-determined low point. With my improved type of thermostat switch I am enabled to automatically take care of all such desired 80 features in the operation of the system.

85 My adjustable contacts may be set so as to open within a very close range of each other, so that very accurate control of the motor, and consequently accurate control of the heat generated by the burner, may be maintained. This is not of course a desirable feature but is frequently of vital importance, as for instance in connection with 90 the heat of incubators, dehydrators and other plants where a great variation in temperature is apt to be disastrous.

95 My thermostat switch, properly adjusted for the different conditions of operations involved, may be also used in refrigerating plants, where the maintaining of the temperature at an even low point is as important as keeping up an even high temperature is in other plants and establishments.

100 A further object of the invention is to produce a simple and inexpensive device and yet one which will be exceedingly effective for the purpose for which it is designed.

These objects I accomplish by means of 105 such structure and relative arrangement of parts as will fully appear by a perusal of the following specification and claim.

110 In the drawings similar characters of reference indicate corresponding parts in the several views:

Fig. 1 is a front view of a thermostat

- switch used for hot water or steam, showing my arrangement of contacts therein; the contacts being in normal or low temperature positions.
- 5 Fig. 2 is a similar view, one set of the contacts being shown broken by expanding of the Bourdon tube by a certain temperature.
- 10 Fig. 3 is a vertical section on the line 3—3 of Fig. 1.
- Fig. 4 is a front view of a hot air thermostat switch showing my arrangement of contacts therein; the contacts being in normal or low temperature positions.
- 15 Fig. 5 is a similar view, showing one set of the contacts broken by the expansion of the diaphragm due to a certain heat.
- Fig. 6 is a vertical section on the line 6—6 of Fig. 5.
- 20 Fig. 7 is a perspective view of an adjustable tube holding bracket detached.
- Fig. 8 is a motor circuit diaphragm showing one arrangement of wiring in which my switch may be interposed to control the 25 operation of the motor.
- Referring now more particularly to the characters of reference on the drawings, and to Figs. 1, 2 and 3, the steam or hot water thermostat comprises a casing 1 in which is 30 mounted a common form of Bourdon tube 2 in which an expansible fluid is sealed as is customary. One end of the tube is fixed to the casing while the other end is free.
- Pivoted in the back of the casing is a 35 bracket 3 having a horizontal flange 4 above the pivot and a vertical arm 5 depending below said pivot. A link 6 is flexibly connected to the arm and to the free end of the tube, so that when the tube expands the 40 bracket is turned on its pivot as an axis. These parts are commonly employed in switches of this character and of themselves form no part of my invention.
- Secured onto and depending from the 45 flange 4 is a cradle 7 in which is supported a horizontal glass tube 8 whose axis is at right angles to the pivot of the bracket 4.
- A small quantity of mercury 9, in connection with an inert gas, is contained in the 50 tube which is sealed.
- This mercury is free to travel from one end of the tube to the other and when at one end makes electrical connection between two longitudinally disposed contact points 55 10 which project into the tube adjacent that end.
- When the Bourdon tube 2 is cold or in a non-expanded condition, the tube 8 will then lie on a slope sufficient to cause the mercury to contact with the points 10. This slope is 60 in that direction such that an expansion of the Bourdon tube will cause the slope to be reversed relative to a horizontal plane.
- Fixed in connection with the flange 4 and 65 projecting upwardly from the outer end
- thereof is a rigid extension 11, behind which is an L-shaped bracket 12. The vertical leg of this bracket abuts against the extension 11 and is adjustably clamped thereto by a pivotal screw 13. Fixed on and projecting 70 up from the horizontal leg of the bracket 12, in vertical alinement with the cradle 7 but in opposed relation thereto, is a similar cradle 14, which supports a tube 15 of the same character as the tube 8. The tube 15 also contains a quantity of mercury 16, sealed in the tube in connection with an inert gas and has longitudinally spaced contact points 17 projecting thereinto at the same end as the contacts 10 in the tube 8. 75
- Flexible leads 18 extend from the different contact points to binding posts 19 in the casing, at which posts connections are made with the circuit of a motor or other electrical mechanism controlled by the switch. 80
- The tube 15 is initially adjusted and set, by means of the screw 13, so that said tube has a greater slope than the tube 8 and in the same direction. The degree of difference in this slope depends on the conditions of 90 operation of the apparatus in connection with which the switch is to be used.
- It will therefore be seen that with the expansion of the Bourdon tube, the tube 8 will gradually move from its initial slope to a true horizontal position, and then beyond such position to rest at a slope the reverse of that originally had. The mercury being free to flow will of course travel to the lowest point of the tube. The result is that said 95 mercury will leave the contact points 10 and the latter will therefore be disconnected or broken and the switch opened.
- The slope at which the tube 15 is set, however, is such that its initial slope has not 100 been entirely eliminated when the contacts 10 are broken, so that the contacts 17 still remain closed. A further expansion of the Bourdon tube will ultimately cause a reversal of slope of the tube 15 to be had, so 105 that the contacts 17 will then also be broken, the contacts 10 of course remaining broken all this time.
- The amount of additional expansion of the 110 Bourdon tube (which is governed by the amount of additional heat) necessary to thus break the contacts 17, of course depends on the relative setting of the two tubes, which as above stated, may be adjusted to suit any conditions.
- The type of switch shown in Figs. 4 to 7 is one actuated by differences in air temperature, and is placed in the room in which the air is to be maintained at a certain temperature. 115
- This device comprises a back plate 20 on which, near the bottom, is mounted an expansible diaphragm 21 secured with an expansible and sensitive fluid which is sealed therein. A horizontal shaft 22 extends out- 120
- 125
- 130

wardly from the plate 20 at right angles thereto a certain distance above the diaphragm, said shaft being mounted in said back plate and in support 23 at its outer end.

- 5 Turnable on the shaft 22 is a bracket 24 having an arm 25 depending from its inner end. This arm is engaged by the upper end of a laterally yieldably connection means indicated at 26, and which extends thence to 10 the diaphragm. This arrangement, which is not novel with me, causes the bracket to be rotated on the shaft one way or the other with the vertical expanding and contracting movement of the diaphragm, while preventing 15 any great expansion of the diaphragm from possibly straining or breaking any parts of the structure. A manually controlled regulating structure illustrated at 27 acts on the diaphragm in the usual manner 20 to control the amount which said diaphragm must expand before causing the switch to be opened, so that the device will function when a predetermined room temperature has been reached. This mechanism also is not 25 novel with me, being already in use in instruments of this general type.

My contact structure, which I incorporate in connection with these standard parts, comprises a horizontal tube 28 mounted in a 30 cradle 29 which depends from and is rigidly fixed on the bracket 24. Contacts 30 project into said tube adjacent one end thereof, and are adapted to be connected by mercury 31 in said tube. This tube, when the diaphragm 35 is in its normal unexpanded condition, is set at such a slope that the mercury then engages said contact points.

Depending from the bracket 24 in front of the tube 28 is a vertical flange 24^a, the 40 shaft 22 passing therethrough. Turnable on the shaft in front of the flange 24^a and abutting thereagainst is a flange 32 formed as part of a cradle 33 which supports a tube 34 of the same nature as the tube 28. The 45 flange 32 is provided with an arcuate slot 35 under the shaft through which projects a screw 36 mounted in the flange 24^a, said screw being operable from the front of the device.

50 It will therefore be seen that upon loosening said screw the cradle 33 may be turned one way or the other about the shaft 22 as an axis, and the slope of the tube 34 relative to the tube 28 adjusted accordingly. When 55 the desired setting of the tube 34 is obtained the screw 36 is tightened up, binding the cradle 33 to the bracket 24 and of course causing the respective tubes mounted on such parts to turn as a unit.

60 The tube 34 carries contact points 37 arranged in the same relation as in the tube 28 and at the same end, said contact points being adapted to be engaged by freely movable mercury 38 contained in said tube.

65 The tubes 28 and 34 are set relative to each

other so that with the expansion of the diaphragm, the slope of the tube 28 will be reversed and the contacts broken before the initial slope of the tube 34 is lessened sufficiently to cause the mercury to disengage the 70 respective contacts. The functioning of this type of switch is therefore the same as that first described.

In Fig. 8 I have shown a circuit in which the first disclosed type of thermostat is interposed, though the latter type could be used instead of the same or in connection therewith.

In this circuit, 39 and 40 represent positive and negative main line wires, and 41 80 a motor driving an oil burner or other apparatus. A lead 42 from one of the contacts 10 leads direct to one terminal of the motor, the other terminal of which is connected to the main line 40 by a lead 43. A 85 lead 44 from the other contact 10 is connected to the lead 42, with a resistance 45 interposed therein.

A lead 46 from one of the points 17 is connected to the positive main wire 39, while 90 a lead 47 from the other one of said points 17 is connected to that one of the points 10 to which the resistance lead 44 is connected.

It will therefore be seen that if both sets 95 of contacts are engaged by the mercury, a current will flow from lead 39, through lead 46, to and through contacts 17, through lead 47 to and through contacts 10, through lead 42 and motor 41, to the main lead 40 through lead 43.

When contacts 10 are broken, that portion 105 of the lead 42 adjacent its contact 10 is out of the circuit. The current will then flow from lead 39 through lead 46 to and through contacts 17, through lead 47 to that contact 10 to which it is connected, and through lead 44 and resistance 45 to the motor, causing the latter to be slowed down.

If such slowing down does not have the 110 desired temperature reducing effect and the Bourdon tube continues to expand, the contacts 17 are finally broken, which breaks the entire circuit to the motor.

From the foregoing description it will be 115 readily seen that I have produced such a device as substantially fulfills the objects of the invention as set forth herein.

While this specification sets forth in detail the present and preferred construction 120 of the device, still in practice such deviations from such detail may be resorted to as do not form a departure from the spirit of the invention as defined by the appended claim.

Having thus described my invention what 125 I claim as new and useful and desire to secure by Letters Patent is:

A thermostat switch comprising a contact structure consisting of a substantially horizontal tube containing a conducting liquid 130 and spaced contacts depending into the tube

adjacent one end thereof, a turnable bracket on which said tube is mounted, an element movable by varying temperature conditions, connecting means between the element and bracket for turning the latter when said element moves, another contact structure and including a second tube, a bracket in which

said second tube is mounted and itself turnably mounted on the first named bracket, 10 and clamping means for maintaining the last named bracket in any desired position relative to said first bracket.

In testimony whereof I affix my signature.

IRVING EDWARD SMITH.
